US0D1003137S

(12) **United States Design Patent** (10) **Patent No.:** **US D1,003,137 S**
 Bert et al. (45) **Date of Patent:** **** Oct. 31, 2023**

(54) **HEDGE TRIMMER**

(71) Applicant: **INNOVATION FABRICATION COMMERCIALISATION INFACO**, Cahuzac-sur-Vere (FR)

(72) Inventors: **Edouard Bert**, Labege (FR); **Davy Delmas**, Broze (FR)

(73) Assignee: **INNOVATION FABRICATION COMMERCIALISATION INFACO**, Cahuzac-sur-Vere (FR)

(**) Term: **15 Years**

(21) Appl. No.: **35/513,988**

(22) Filed: **Mar. 25, 2022**

(80) **Hague Agreement Data**

Int. Filing Date: **Mar. 25, 2022**

Int. Reg. No.: **DM/219769**

Int. Reg. Date: **Mar. 25, 2022**

Int. Reg. Pub. Date: **Apr. 8, 2022**

(51) **LOC (14) Cl.** **08-05**

(52) **U.S. Cl.**

USPC **D8/61**
